UNITED STATES PATENT OFFICE.

HARRY W. RANSDELL, OF INDIANAPOLIS, INDIANA, ASSIGNOR OF ONE-THIRD TO THEODORE A. MEYER AND ONE-THIRD TO LOUIS H. KNU, BOTH OF INDIANAPOLIS, INDIANA.

LATHE-TURRET.

1,268,277.

Specification of Letters Patent.

Patented June 4, 1918.

Application filed December 1, 1916. Serial No. 134,412.

To all whom it may concern:

Be it known that I, HARRY W. RANSDELL, a citizen of the United States, residing at Indianapolis, Marion county and State of Indiana, have invented and discovered certain new and useful Improvements in Lathe-Turrets, of which the following is a specification.

My invention relates to lathe turrets and its objects are to provide a turret head of rigid construction capable of supporting rectangular or forged tools of various sizes, one advantage of which is to enable the employment of tools having a greater body of metal than usual, thus effecting a greater 10 radiation of heat and enabling rapidity of operation to be obtained, such head being constructed to permit the adjustment of said rectangular tools at any desired angle to the 15 axis of the turret, to provide a turret adapted to receive both tools of said rectangular form and box or round shank tools, to provide means co-operating with a turret thus formed to enable the tools to be brought 20 close to the center while at the same time obtaining a rigid, closely fitting bearing for 25 the turret; to provide means of a strong and positively acting construction for effecting 30 both the locking and locating actions of the 35 turret in a single movement of an operating handle; to provide means whereby such handle may be located at the bottom of the turret near the level of the other operating handles of the adjusting screws; to provide 40 means for effectively centering the turret relatively to the spindle and to generally improve 45 the construction of lathe turrets.

With these objects in view, my invention is embodied in preferable form in the construction and arrangements hereinafter set forth and illustrated in the accompanying drawings.

In these drawings, Figure 1 is a perspective view of a lathe turret showing the invention applied thereto; Fig. 2, a top plan view; Fig. 3, a vertical central section and Fig. 4, a side view in elevation partly broken away at right angles to Fig. 3.

Referring to the drawings, 3 is a cross slide mounted on the carriage carried by the bed of the lathe. Fixed on this cross slide is a cylindrical turret supporting base member 4 on which is rotatably mounted a turret 5 having a hexagonal head and made of a single piece of metal. The base portion of

the turret is provided with a flange 6 having a flat horizontal face adapted to bear upon the upper flat face of the slide and it is also provided with a depending taper portion 7 having a taper fit and bearing 60 against a tapered or cone-shaped bearing in the upper central portion of the slide. The turret is not only centered by this tapered fit in the cross slide but also is provided through such fit with a self-adjusting and self-compensating bearing which will take 65 up the wear by permitting the turret to move down in the bearing as the wear occurs, thus always maintaining an accurate seating of the turret and preventing side 70 movements due to wear. The turret is provided with an annular groove 8 which is engaged by gibbs 9 which serve to hold the turret down against the slide. These gibbs engage the turret with a running fit, which 75 permits of the rotatable adjustment of the latter. The gibbs are clamped in position by means of screw bolts 11 and after the gibbs are once adjusted and fixed in place, it is 80 unnecessary to remove them except to replace the turret head.

Engaging the turret and extending through a semi-cylindrical hollow column 12 integral with the turret, is a bolt 12' provided at its upper end with a nut 13 and at 85 its lower end with a head 14 lying in a chamber 15 formed in the cross slide. This bolt may be of small diameter as compared with bolts customarily employed in turrets, since it merely acts as a member, to be engaged by the locking means and does not have to perform the functions of a centering and bearing member as is usual, such functions being performed by the taper or cone fit between the turret base and the slide. 90

The turret is adapted to be pulled down into its taper seat by pressure exerted below the same and to this end the head 14 of the bolt is spaced from the lower face of the turret base and extending over and against 100 the upper face of this head is the horizontal flange 16 of a clamping gib which is adapted to be moved downwardly to exert a downward pressure on the bolt for the purpose of clamping the turret against rotatable movement in its tapered seat and to be released therefrom by an upward movement to permit the turret to be turned. To accomplish this result, the vertical wall 17 105 of the gib is provided with interior threads, 110

preferably right hand threads which engage corresponding threads, 18, formed on the upper end of a fixed double screw, the lower and smaller portion 19 of which is threaded 5 into the slide. A locking screw pin 20 serves to hold this double screw from turning with respect to the slide.

Engaging the gib is the threaded stem 21 of a horizontally movable operating handle 10 22 which projects through a curved slot 23 formed in the turret supporting base 4 of the cross slide.

Formed in the lower face of the turret is an annular series of holes in each of which 15 is a hardened tapered bushing 24. Adapted to engage any one of these openings is a single positioning or locating pin 26 movable in a bushing 25 mounted in a vertical opening formed in the base member 4 and 20 which pin is provided with a tapered head 27 whereby a close and accurate fit is obtained with the hole in the turret into which it may be projected. Below this pin is mounted an upwardly pressing spring 28, 25 affording means to carry the pin upwardly. The pin is provided with a slot 29 which is engaged by one arm 30 of a bell crank lever, the other arm 31 of which projects upwardly into the slot 23 in line with the 30 movement of the handle 22, whereby as the handle is moved in one direction, it will contact with said arm 31 and depress the lever so as to draw the pin downwardly out of engagement with the hole in the turret 35 and as the handle is moved in the other direction, the lever and pin will be permitted to be forced upwardly by the spring 28 so that the pin is ready for engagement with the next socket in the turret with which it 40 may be moved into registry.

The turret is adapted to support both round shank or box tools and rectangular or forged tools, the object of which is to enable the utilization of both kinds of tools 45 without changing turrets and the turret thus formed is also provided with means whereby substantially any angular adjustment of the forged tools with respect to the axis of the turret may be obtained which is 50 of great advantage in all lathe work and particularly in respect to enabling the performance of successive operations of different natures upon a single piece of work, as, for instance, boring, turning, facing and 55 chasing, without removing or re-adjusting the respective tools, after they have once been set to the required positions. To this end the turret is provided with a series of flat vertical faces in which are formed 60 round sockets 32 adapted to receive the shanks of box tools. The remaining portion of the head is cut away intermediate its upper and lower portions between the end walls of the two innermost faces in which 65 are formed the round sockets, to provide a

horizontally open curved slot 33, between an upper wall 34 and a lower wall 35 of said head. To preserve the rigidity of the head 6, the upper and lower walls 34 and 35 are preferably permanently connected 70 by means of corner bolts 36.

Mounted in the upper wall 34 of the turret is a series of set screws 37 which are disposed near the outer edge of the wall and of which three are shown as provided for each 75 face of the turret. Mounted within the outer series of set screws is an inner smaller number of set screws 38. Both sets of said screws are adapted to be forced against the inner end of the square or forged tools and owing to the plurality of screws for each face provided by the outer row any tool may be adjusted at substantially any desired angle to the axis of the turret, in such adjustment the tool being clamped by any one 80 of the outer set screws and the inner end of the tool being clamped by the inside set screw of that face. 40 are set screws adapted to engage the round shanks of the box tools.

Mounted loosely in a socket on the slide is a pin 41 which is adapted to enter a hole formed in the carriage on which the slide is mounted and which pin and hole are so located that when they are in engagement the 90 turret will be carried exactly opposite the center of the spindle. The pin and hole thus afford a positive stop which will prevent such a straining of the slide relative to the carriage, possible in the usual form of 95 stops, as to permit the turret to be moved slightly off center.

In the assemblage, use and operation of the turret, the bolt 12' is engaged with the 100 turret and with the gib 16 by passing it upward through the gib and into its socket at the upper end of the head at which upper end it is engaged with the nut 13. The head 14 of the bolt is smaller in diameter than the inner threaded circumference of the vertical wall of the gib, thus permitting the head to pass the threads. The turret is then seated and clamped by the gibs 9 with a running fit against the same, in which position it will have a true fit in its taper socket 110 and on the flat face of the slide base. The double screw 18—19 is inserted in place and engaged with the gib and located in 115 position by the pin 20.

Any box tools required are inserted in the 120 round openings 32 and clamped in position by the set screws 40. At the same time, if desired, any forged tools that it may be necessary to use in successive operations of the lathe are clamped into position in the 125 slot 33 by means of the set screws 37 and 38, and angular adjustment permitted by the three laterally spaced set screws for each face of the outer series of screws.

It will be seen that owing to the fact that 130

the bearing and centering functions of the turret are obtained by the taper or cone seat thereof and, therefore, only a small clamping bolt is necessary, the tools may be carried in 5 closely to the center of the turret, thus affording a long and rigid bearing support for them which will serve to prevent vibration and chattering thereof. The elongated slot permits tools of greater body to be employed, thus effectually radiating heat. The 10 turret consists of an integral body of metal, which is substantially solid at the portion having the round sockets and thus a rigid construction is obtained. The central integral column 12 further insures the rigidity of the head. The slot 33 may be elongated to a greater length than shown in the drawing and in fact around the entire circumference if desired.

20 In order to lock and locate the turret in the rotative adjusting movement of the latter, when it is desired to bring any one of the tools into engagement with the work, and assuming first that it is desired to lock the 25 turret in place, the handle 23 is pulled toward the operator, that is toward the front as viewed in Fig. 1, which movement by means of the engaging threads 18 on the double screw and the movable gib will cause 30 said gib to be moved downwardly so as to clamp its horizontal flange 16 against the upper face of the head 14 of the bolt 12', thus forcing the turret down rigidly into its tapered seat in the slide base 4 and holding 35 the turret against rotatable movement. At the same time the pin 27 will be projected into that one of the sockets 24 opposite which the pin has been carried. The engagement of this pin with the socket, serves 40 to properly locate the turret on the slide and prevent any side or circular loose movement thereof after such adjustment.

It will be seen that this release of the pin to permit its projection by the spring 28 and 45 the locking of the gib against the bolt is accomplished by a single movement of the handle in one direction.

To unlock the gib from the bolt and withdraw the positioning pin from the turret, 50 the handle is moved in the opposite direction, whereupon the gib will be unscrewed from the threads 18, of the fixed screw, thus unclamping the turret from the slide and in such movement of the handle it will be carried against the arm 31 of the bell crank 55 carrying downward the pin 25 out of the socket bushing 24, so as to permit the turret to be moved rotatively. This release of the gib and the positioning pin is thus also obtained by a single movement of the handle in 60 one direction.

It will be seen that, owing to the fact that the clamping and positioning pin mechanism is located below the turret, it is possible to 65 place the operating handle adjacent the level

of the other usual operating handles of the lathe, such as the slide feed screw handle, thereby facilitating ease and rapidity of operation in the adjustment of the lathe turret.

The pin 41 on the slide by its engagement 70 with the hole in the carriage affords a fixed centering stop for the slide and turret which it is impossible to strain, thus providing an advantage over the usual form of exterior stop against which the slide is 75 adapted to be moved and which sometimes can be strained so as to carry the slide somewhat out of center.

Having thus described my invention, what 80 I claim is:

1. A lathe turret made of an integral body of metal and having an opening therein with a tool supporting base lying in a horizontal plane and of sufficient radial depth to receive the shank of a tool so mounted as 85 to project longitudinally from the central part of the turret, said opening being elongated in horizontal planes beyond the width of the tool shank across the line of the depth of the opening to permit of the angular adjustment of the tool or the use of tools of different sizes, and clamping means for the tool exerting pressure in a vertical line.

2. A lathe turret formed of an integral body having a horizontal slot cut therein 95 which extends inward toward the center of the turret to a depth sufficient to receive a tool projecting longitudinally from the center, a clamping member above the tool and adapted to exert vertical pressure thereon, 100 said slot being horizontally elongated beyond the width of the tool shank across the line of the depth of the opening to permit of the angular adjustment of the tool around the clamping means as a pivotal center.

3. A lathe turret having a portion of its head provided with circular sockets for receiving round shank tools and an integral portion thereof provided with a flat plane bearing surface extended inwardly adjacent 110 the center radially of the turret and adapted to receive a rectangular tool and elongated beyond the width of the tool.

4. A lathe turret made of an integral body of metal and having a portion provided with 115 round sockets and having a single horizontally elongated cut-away part adapted to receive rectangular tools of varying sizes or hold them at various angles.

5. A lathe turret having a plurality of faces and having sockets to receive the round shanks of tools in several of said faces, and having a flat plane bearing surface in each of the other faces, said surface being extended inwardly radially adjacent 120 the center of the turret and widened beyond the width of a rectangular tool and adapted to receive the latter and a plurality of tool clamping members for each rectangular tool receiving face.

6. A lathe turret having a portion of its head provided with round tool sockets and having the remaining portion of its head cut away to provide a continuous horizontal opening adapted to receive rectangular tools.
7. A lathe turret having socket means for holding round shank tools and having a circularly elongated horizontal slot adapted to receive rectangular tools and permitting them to be adjusted at different angles, and a plurality of tool clamping screws at each face of the turret along the border of said slotted portion whereby a tool may be held at various angles.
- 10 8. A lathe turret having socket means for holding round shank tools and having an elongated horizontal slot adapted to receive rectangular tools, a plurality of tool clamping screws for each slotted face of the head, arranged adjacent the edge of said head, and an inner concentric series of tool clamping screws.
- 15 9. A lathe turret having a head portion provided with round sockets and having a portion provided with a continuous cutaway horizontal slot adapted to receive rectangular tools, an outer series of clamping screws around the border of said slotted portion, said screws being closely adjacent one another, and a smaller number of inner concentric clamping screws at said slotted portion whereby a rectangular tool may be engaged with anyone of said outer screws and with an adjacent inner screw to fix the tool at any desired angle.
- 20 10. A lathe turret having a portion provided with round tool sockets, and the remaining portion having a continuous horizontal slot forming upper and lower walls between which rectangular tools are adapted to be clamped, and bolts connecting said upper and lower walls of the slotted portion.
- 25 11. In combination with a lathe turret, a slide on which said turret is mounted for rotatable adjustment, a gib fixed to the slide and engaging the turret with a running fit
- 50 to prevent upward movement of the turret, a bolt extending through the turret, a tapered seat between the turret and slide providing a centering and bearing surface, an adjustable gib below the turret adapted to engage said bolt and exert a downward pressure thereon and means 55 for operating said latter gib.
- 55 12. In combination with a lathe turret, a slide on which said turret is mounted for rotatable adjustment, a screw fixed to said slide below the turret, a threaded gib engaging said screw and adapted to exert a downward pull on the turret to lock the same against the slide, a handle fixed directly to said gib for turning the same, a positioning pin between the turret and slide 60 and pin-operating means adapted to be actuated by the handle in the clamping movement of the latter.
- 65 13. In combination with a lathe turret, a slide on which said turret is mounted for 70 rotatable movement, a gib fixed to the slide and having a running fit with the turret to prevent upward movement of the latter, a bolt extending through said turret, a threaded clamping gib below said turret and engaging the head of said bolt, a screw fixed to the slide and engaging said threaded gib, a tapered seat between the turret and slide and a reciprocating handle secured to the threaded gib for operating the same.
- 75 14. In combination with a lathe turret, a slide on which said turret is mounted, a carriage for the slide, a centering stop pin carried by the slide, said carriage having a socket hole into which said pin is adapted 80 to be projected, said pin and socket when in registry fixing the center position of the turret relative to the spindle.
- 85 In witness whereof, I have hereunto set my hand and seal at Indianapolis, Marion county, Indiana, this 16th day of November, A. D. nineteen hundred and sixteen.
